UNITED STATES PATENT OFFICE

152,185

DESIGN FOR A COMBINED TOY SINK, WATER DISPENSER, AND RECEIVER

Herman Barr, New York, N. Y.

Application May 7, 1947, Serial No. 138,891

Term of patent 3½ years

(Cl. D34—15)

To all whom it may concern:

Be it known that I, Herman Barr, citizen of U. S. A., residing at New York, in the county of New York and State of New York, have invented a new, original, and ornamental Design for a Combined Toy Sink, Water Dispenser, and Receiver, of which the following is a specification, reference being had to the accompanying drawing, forming part thereof.

Fig. 1 is a perspective view of the combined toy sink, water dispenser and receiver, showing my new design;

Fig. 2 is a side view thereof; and

Fig. 3 is an exploded rear perspective view of the device as it would appear with the water receiver detached therefrom.

I claim:

The ornamental design for a combined toy sink, water dispenser, and receiver, as shown.

HERMAN BARR.
